UNITED STATES PATENT OFFICE.

OSCAR RUST, OF ST. JOSEPH, MISSOURI.

WELL-DRILLING MACHINE.

SPECIFICATION forming part of Letters Patent No. 257,767, dated May 9, 1882.

Application filed February 7, 1882. (No model.)

To all whom it may concern:

Be it known that I, OSCAR RUST, of St. Joseph, in the county of Buchanan and State of Missouri, have invented a new and useful Improvement in Well-Drilling Machines, of which the following is a full, clear, and exact description, reference being had to the annexed drawings, forming part of this specification.

This invention relates to well-drilling machines in which the drill-rod is operated by an oscillating lever connected thereto by a rope; and the invention consists in certain improvements relating to the construction of the mast and the arrangement of the lever and its operating mechanism with respect to each other, together with certain other minor improvements, as will be hereinafter described.

In the accompanying drawings, Figure 1 is a side elevation of my improved well-drilling machine. Fig. 2 is a side elevation of the same, reversed and partly in section, with the top of the mast broken away. Fig. 3 is a plan view of the machine, with the mast and braces in horizontal section; and Fig. 4 is a perspective detail of the lever, showing the improved shackle for holding the sheave.

In well-drilling machines of the class to which my invention belongs the mechanism for operating the lever has heretofore been placed at the top of the supporting-frame, while the lever has been fulcrumed at the bottom of the frame in such manner that its oscillation shall be above a horizontal plane. With this construction an angle must be formed in the tumbling-rod to reach the shaft carrying the arm that oscillates the lever, and unnecessary friction is thus caused in the joints of the tumbling-rod. Besides, the location of the lever-operating mechanism at the top of the frame causes a vibration of the machine, which results in straining and otherwise weakening the frame. I therefore locate the shaft *a* of the drive-wheel *b* at the bottom of the frame *A* on a level with the fulcrum of the lever *c*.

To accommodate the drive-wheel and the oscillation of the lever, I excavate the earth immediately underneath these parts, so as to form a suitable recess without interfering with the foundation upon which the frame rests.

The lever is thus adapted to oscillate above and below the plane of its fulcrum, and owing to the shaft *a* being located at the center of the sweep of the lever less power will be required for driving the arm *d* on the said shaft 55 to oscillate the lever than when the said shaft is located near the upper extreme limit of the sweep—that is to say, at the top of the frame—because in the former case a shorter arm will suffice to oscillate the lever than in the latter 60 case. With this construction the power is applied at the base of the machine with a straight tumbling-rod, by which the usual unsteadiness and vibration of the frame are avoided.

The lever *c*, which is provided with a cross-piece at one end in the usual manner, and journaled in suitable bearings in opposite sides of the frame, is provided with a shackle, *e*, which is secured to its upper surface at a point near the center for supporting the sheave *f*.

The shackle is constructed with an opening, *g*, in one side, through which the rope which passes under the sheave may be removed at will for the purpose of allowing the rope to be wound evenly upon the drum *h* from the 75 sheave *i* at the top of the mast *B*.

Heretofore no means have been provided for detaching the rope from the sheave on the lever; but it has been necessary to wind the rope on the drum from this sheave, so that on 80 account of the close proximity of the sheave to the drum the rope could not be wound evenly.

I am aware that a swiveled sheave has been used on the lever; but this cannot secure the desired result so well as removing the rope from 85 the sheave on the lever and allowing it to wind from the sheave *i* at the top of the mast.

The mast *B* is located at one end of the frame *A* in line with the longitudinal center thereof, so that the lever *c* and operating-arm *d* shall 90 lie in a vertical plane cutting the said center. The object of so arranging these parts is obvious, since even a slightly-lateral arrangement would tend to throw the strain to one side of the frame, and thus prevent an equal 95 distribution of pressure upon the timbers.

To increase the strength of the mast, I construct it of two upright timbers, *b'* *b''*, which are secured to opposite sides of intervening blocks *b''*, arranged at suitable intervals apart. 100

Formerly masts have been constructed of single timbers having slots mortised therein for receiving the sheaves; but such a construction tends to weaken the mast, and, besides, 5 two timbers put together in the manner described will form a much stronger mast than can be made of a single piece. In the top of this mast is journaled the sheave *i*, over which passes the rope to which the drill *j* is secured. 10 The opposite end of the rope is wound upon the drum *h*, which is provided with a ratchet and pawl, as usual, for holding the drum to prevent the rope from being unwound. The rope of course is to be let out as the depth of 15 the well increases.

When it is desired to wind the rope upon the drum to withdraw the drill from the well the drum *h* is thrown into gear with the drive-wheel *b* by means of a lever, *l*, which moves a 20 sliding pinion, *m*, having a sprocket-wheel, *n*, connected therewith, and chained with a sprocket, *o*, on the drum. By means of this pinion *m* being made to gear with the drive-wheel *b* a rapid motion is given to the drum 25 without multiplying the machinery to an unnecessary extent.

At a point near the fly-wheel *p* is located a second drum, *q*, having a windlass, and provided with a shifting-lever, *r*, by which the 30 flange of the drum shall be thrown into frictional contact with the side of the fly-wheel. In this manner the drum is operated to hoist the slush-bucket rapidly from the well without the use of the usual intermediate gearing 35 for connecting the drum with the fly-wheel. Upon this drum is wound the rope *s*, which passes over a sheave, *t*, in the mast, and is connected to the bucket *u*. By thus gearing the drum *q* with the fly-wheel the bucket may be 40 drawn up with great rapidity and the drum disengaged from the fly-wheel without stopping the motion of the machine.

Having thus described my invention, what I claim, and desire to secure by Letters Patent, 45 is—

1. A well-drilling machine having the driving-shaft located at the center of the arc described by the drill-operating lever, whereby the said lever shall be operated by the short-

est arm possible on the driving-shaft, substantially as shown and described, and for the purpose set forth. 50

2. A well-drilling machine having the driving-shaft located at the base of the supporting-frame, and the fulcrum of the drill-operating lever on a horizontal level with the said shaft, whereby power shall be gained in the operation of the lever by the arm on the said shaft, and the frame shall be rendered steady when the machine is in motion, substantially 55 as set forth.

3. In a well-drilling machine, the combination, with the lever *c*, of an open shackle, *e*, for supporting the sheave *f*, substantially as shown and described, whereby the rope may be removed from the sheave to allow it to be wound 60 evenly on the drum, as set forth. 65

4. In a well-drilling machine, the mast composed of two vertical side pieces placed nearly in juxtaposition with each other, and having 70 spaces for journaling the sheaves formed by intervening blocks inclosed between the side pieces, substantially as shown and described, whereby the spaces shall be formed without mortising the mast, and the upper and lower 75 sheaves shall be supported by the side pieces immediately at the sides thereof, as specified.

5. In a well-drilling machine, the combination, with the drum *h*, carrying the drill-rope, of the sliding pinion *m*, gearing directly with 80 the drive-wheel *b*, and connected with the drum, substantially as shown and described, whereby the drum shall be wound with increased rapidity in hoisting the drill from the well, as set forth. 85

6. In a well-drilling machine, the combination, with the fly-wheel *p*, of the flanged drum *q*, carrying the rope of the slush-bucket, and adapted to be shifted to throw the flange into frictional contact with the side of the fly-wheel, 90 substantially as shown and described, whereby a rapid motion shall be given to the drum without the use of intermediate gearing between the drum and the fly-wheel, as set forth.

OSCAR RUST.
